ABSTRACT: A semiconductor device with at least one PN junction and a method of manufacturing the same wherein a passivating film or a surface film for insulation is made of a chemical mixture of oxides composed of SiO_2 — TiO_2 so that the breakdown voltage and electrical stability of said PN junction can be increased. This effect is based on the suppression of movement of alkali ions in said film with the mixture of oxides. The film with the mixture of oxides composed of SiO_2 — TiO_2 is obtained with a method where vapors of organo-oxy-silicon compound and organo-oxy-titanium compound are led onto a substrate, with which is heated and sustained at a predetermined temperature, and pyrolyzed on a surface of the substrate to make the film.

**SEMICONDUCTOR DEVICE AND METHOD OF
MANUFACTURING SAME**

The present invention relates to a semiconductor device in which a passivating film is formed on the surface of one or more PN-junctions included in said semiconductor device such as a diode or a transistor.

A silicon dioxide film (SiO_2) has been used widely as a passivating film for semiconductor devices having PN-junctions. It is also known that if there are alkali ions, for example sodium ions, in the SiO_2 film, they have a bad influence upon the breakdown characteristics and secular variation characteristics and it is a fact that many methods to obtain a stable SiO_2 passivating film with less alkali ions are adopted especially in the manufacturing process. The object of the present invention is to improve characteristics of a semiconductor device with an SiO_2 film and the invention is characterized by using a homogeneous film with a mixture of oxides composed of SiO_2 and titanium dioxide (TiO_2) as a surface passivating film in a semiconductor device.

FIG. 1 is a schematic cross-sectional view of a semiconductor device according to the present invention,

FIG. 2 and FIG. 3 are views showing characteristics of a passivating film according to the present invention.

FIG. 1 is a schematic cross-sectional view of a diode as an example of a semiconductor device according to the present invention and showing the situation where said film with the mixture of oxides 3 is laid on the surface of the semiconductor device with a PN-junction formed of P-type semiconductor 1 and N-type semiconductor 2. And reference numerals 4 and 5 designate electrodes.

In said film with the mixture of oxides, even if there are an appreciable number of alkali ions, such as sodium ions, which move easily, they are electrically trapped by oxide TiO_2 . Consequently, the film becomes stable and moreover its electric strength becomes high to improve the breakdown characteristics of the device. This can also be proved with FIG. 2. FIG. 2 shows the relative density of sodium in the film (N) with respect to that in the surface (N_s), as a function of the distance from the surface, and also shows movement of sodium ions in a film in accordance with the prior art and in the film with the mixture of oxides according to the present invention. These characteristics are given by observing the distribution of the sodium ions prevented from the surface of the films by heat treatment during 24 hours at 600°C. after the sodium is laid on the surface. In the drawing, *a* and *b* correspond to the case of the SiO_2 film and the case of the film with the mixture of oxides, SiO_2 and TiO_2 in which TiO_2 is mixed by 20 percent.

It is obvious from the drawing that the sodium ions are hard to move in the film composed of the mixture of oxides, SiO_2 and TiO_2 .

The film with the mixture of oxides according to the present invention can be formed with the following method. Organo-oxy-silicon compound, for example tetra-ethoxy-silane ($\text{Si}[\text{OC}_2\text{H}_5]_4$), and organo-oxy-titanium compound, for example, tetra-iso-propyl-titanate ($\text{Ti}[\text{OC}_3\text{H}_7]_4$), are heated and evaporated respectively at a predetermined temperature and mixed, or a little amount of oxygen is added to the mixture, then the mixture is led into a reactant tube with inert gas such as nitrogen or argon and pyrolyzed on the surface of the semiconductor device which is heated and sustained at 250°–500°C. to make the uniform amorphous film with the mixture of oxides, SiO_2 and TiO_2 , on the surface of the semiconductor device. The addition of oxygen promotes the reaction of pyrolysis, especially.

FIG. 3 shows a relation between the volume ratio of TiO_2 mixed into SiO_2 and the electric strength of the film. Referring to FIG. 3, it is obvious that the mixture of TiO_2 into SiO_2 by within about 5–30 percent is remarkably effective.

And the same result may be obtained with so-called multiple layers, which consist of, for example, a first layer of SiO_2 disposed on a semiconductor element, a second layer of a mixture of SiO_2 and TiO_2 formed on the first layer and a third layer of TiO_2 formed on the second layer, as a passivating film. The second layer of the mixture may be dispensed with if so desired so that the third layer may be on the first layer.

As described above, a semiconductor device having the film with the mixture of oxides composed of SiO_2 and TiO_2 according to the present invention as a passivating film improves its passivation effect of SiO_2 for PN-junctions and has good breakdown and secular variation characteristics.

What is claimed is:

1. A semiconductor device including at least one PN-junction having a film for isolation on a surface of said semiconductor device, wherein said film comprises at least one layer of a mixture of silicon dioxide and titanium dioxide, and wherein said titanium dioxide comprises 5–30 percent by volume of said mixture.

2. A device according to claim 1 wherein said film further comprises at least one additional layer of at least one element selected from the group consisting of silicon dioxide and titanium dioxide.

3. A semiconductor device as set forth in claim 1, wherein said film is composed of amorphous silicon dioxide and titanium dioxide.
